UNITED STATES PATENT OFFICE.

JOSEPH BRANSON, OF BROOKLYN, ASSIGNOR TO S. BARON & CO., OF NEW YORK, N. Y.

DESIGN FOR A FABRIC.

SPECIFICATION forming part of Design No. 20,073, dated August 5, 1890.

Application filed May 26, 1890. Serial No. 353,266. Term of patent 7 years.

To all whom it may concern:

Be it known that I, JOSEPH BRANSON, a citizen of the United States, residing at Brooklyn, in the county of Kings and State of New York, have invented and produced a new and original Design for Fabrics, of which the following is a specification.

My invention relates to so-called "cardigan" or "ribbed" goods; and the leading feature of my new design consists in elliptical-shaped open-work figures on the surface of the fabric formed by the surface-ribs.

Reference is to be had to the accompanying drawings, forming a part of this specification, in which similar letters of reference indicate corresponding parts in both the figures.

Figure 1 shows a plan view of the open-work surface of my newly-designed fabric,

and Fig. 2 is a similar view of the opposite surface of the fabric.

The fabric A shows on one surface the ribs *a a'*, forming elliptical-shaped open-work figures B B upon the body C of the fabric, which appears within said figures. The said ribs show at their outer surface a chain or cardigan stitch *c*, the opposite surface of the fabric comprising the straight cardigan ribs *d*, as clearly shown in Fig. 2.

I claim—

The design for fabric, substantially as herein shown and described.

JOSEPH BRANSON.
